[57] CLAIM

The ornamental design for a level, as shown and described.

DESCRIPTION

FIG. 1 is a front and top-left perspective view of a level showing my new design;

FIG. 2 is a rear elevational view thereof;

FIG. 3 is a top plan view thereof;

FIG. 4 is a bottom plan view thereof;

FIG. 5 is a typical end elevational view thereof;

FIG. 6 is another embodiment of my new design of FIGS. 1-5 but without color contrast.

FIG. 1

FIG. 5

FIG. 2

FIG. 3

FIG. 4

FIG. 6
